UNITED STATES PATENT OFFICE.

GEORGE K. ASANO, OF DALHART, TEXAS.

COMBINATION FAN, SCORE-CARD, AND MEGAPHONE.

1,332,789.

Specification of Letters Patent.

Patented Mar. 2, 1920.

Application filed April 18, 1919. Serial No. 291,149.

To all whom it may concern:

Be it known that I, GEORGE K. ASANO, a citizen of the United States, residing at Dalhart, in the county of Dallam and State of Texas, have invented new and useful Improvements in Combination Fans, Score-Cards, and Megaphones, of which the following is a specification.

This invention comprehends the provision of a combination, fan, score card and a megaphone, which can be very cheaply manufactured for free distribution by large business concerns desiring to utilize the invention as an advertising medium.

The invention embodies among other features a handle having means for holding the fan blade associated therewith in either a flat or rolled condition, to provide a fan or megaphone.

Another object of the invention resides in providing the fan blade with means for holding the same in a rolled condition for use as a megaphone.

Other objects and advantages will appear as the nature of the invention is better understood when the following detailed description is taken in connection with the accompanying drawings, the invention residing in the construction, combination and arrangement of parts as claimed.

In the drawings forming part of this specification, like numerals of reference indicate similar parts in the several views and wherein:

Figure 1 is a view in elevation of the device when used as a fan.

Fig. 2 is a vertical sectional view taken therethrough.

Fig. 3 is a perspective view showing the clamping element for the blade in an inactive position.

Fig. 4 is a plan view of the fan blade.

Fig. 5 is a perspective view of the handle with the blade removed.

Fig. 6 is a view showing one end of the blade clamped to the handle subsequent to the rolling of the blade to form a megaphone.

Fig. 7 is a perspective view of the blade in its rolled condition.

Fig. 8 is a transverse sectional view therethrough taken on line 8-8 of Fig. 7.

Fig. 9 is a view showing the fan blade in a rolled condition and partly associated with the handle.

Referring more to the drawings in detail,

10 indicates the handle proper which is provided with a relatively wide end portion, the latter being bifurcated as at 11 to define the separated members 12 and 13 respectively. The handle 10 may be constructed of one piece of material as indicated in Fig. 5, or it may be made up in two parts or halves as shown in Figs. 2, 3 and 9, in which instance the halves are glued or otherwise suitably secured together. The member 13 projects a slight distance beyond the adjacent end of the member 12, and pivoted upon this extended portion of the member 13 is a clamping element 14 for the blade 15. The free end of the clamping element 14 may be secured in any suitable manner to the member 13 in clamping position. As shown in this specific instance, a resilient trip 20 is carried by the free end 75 of the element 14, and provided with an opening 21 adapted to receive the pin 22 projecting from the adjacent side of the member 13.

The blade 15 is preferably constructed 80 from card board, of the outline shown, wherein the opposed side edges incline from the wide or top edge of the blade toward the narrow lower edge thereof, and when the device in its entirety is to be used as a 85 fan, the blade has its narrow end positioned within the bifurcation 11 between the members 12 and 13 respectively. Subsequent to this positioning of the blade, the clamping element 14 is extended across the 90 blade to effectively engage the latter when secured in its position. Each side of the blade 15 is scored as at 16 in a manner similar to a base ball score card, so that in addition to being used as a fan, it can be 95 utilized in the capacity of a score card as will be readily understood. As hereinabove stated, the device is primarily intended as an advertising medium for business concerns, and the blade 15 is of sufficient area 100 to provide reasonable advertising space, and if desired the members 12 and 13 of the handle may be also used for advertising purposes.

In addition to a fan and score card, the 105 invention is further adapted to be used in the capacity of a megaphone by those who do not know how to keep score, as well as those who prefer to root instead of keeping score as the game progresses. For this purpose the blade 15 is provided adjacent each corner with co-operating fastening elements

18 which hold the blade in a rolled condition to provide a megaphone, as clearly shown in the drawing. The fastening means carried by the blade for this purpose may be 5 of any shape or form or size without departing from the spirit of the invention. While the blade in a rolled condition may be used as a megaphone independently of the handle 10, for the convenience of handling 10 the megaphone I utilize the clamping element 14 for holding the megaphone associated with the handle as shown. In the association of these parts, the blade may be initially rolled and secured in this condition, and then subsequently slipped over the clamping element 14 prior to fastening the latter in its clamping position, or the blade in a flattened condition may be arranged 15 upon the handle in a manner illustrated in 20 Fig. 9. In this instance, the clamping element 14 extends longitudinally of the blade across the latter and is initially secured to the member 13 in clamping position. Subsequent to this operation the blade can be 25 easily rolled and the fastening elements 18 engaged to maintain the blade in its rolled condition. The device in its entirety then may be conveniently handled and used as a megaphone.

30 While I have shown and described what I consider the preferred embodiment of the invention, I desire to have it understood that I do not limit myself in this connection, inasmuch as such changes may be resorted to 35 when desired as fall within the scope of what is claimed.

What I claim is:—

1. A combined fan and megaphone comprising a handle having a broad extremity,

the extremity being slotted, a fan blade removably fitted within the slot, means for holding the blade in a rolled condition, and a clamping element adapted to effectively engage the blade to hold the same upon the handle in either a flat or rolled condition. 40

2. A combined fan and megaphone comprising a handle having a relatively broad end portion, a fan blade removably associated with the handle, a clamping element pivotally mounted upon the broad end portion, means for holding said blade in a rolled condition, said clamping element being adapted to hold the blade associated with the handle in a rolled or flat condition, and means for securing the clamping element in clamping relation with respect to the broad end portion of the handle. 45

3. A device of the class described comprising a handle, a flat member capable of being rolled, and means for holding the member upon the handle in one position to define a fan, and in another position to provide a megaphone. 60

4. A device of the class described comprising a handle, a flexible blade, means for maintaining the blade in a rolled condition, and means for holding the blade in either of two positions upon the handle to define a fan or megaphone. 65

5. A device of the class described comprising a handle, a flat member capable of being rolled, means for holding the member in a rolled condition, and means for holding the member upon the handle in one position flat to provide a fan, and in another position when rolled to provide a megaphone. 70

In testimony whereof I affix my signature.

GEORGE K. ASANO
